UNITED STATES PATENT OFFICE

139,546

DESIGN FOR A KNIFE OR OTHER ARTICLE OF FLATWARE

Frederick E. Greene, Westport, Conn., assignor to National Silver Company, New York, N. Y., a corporation of New York

Application June 28, 1944, Serial No. 114,223

Term of patent 14 years

(Cl. D22—3)

To all whom it may concern:

Be it known, that I, Frederick E. Greene, a citizen of the United States, residing in Westport, Fairfield County, State of Connecticut, have invented a new, original, and ornamental Design for a Knife or Other Article of Flatware, of which the following is a specification, reference being had to the accompanying drawing, forming a part thereof, in which:

Fig. 1 is a top plan view of a knife or other article of flatware embodying my new design;

Fig. 2 is a side elevation thereof.

I claim:

The ornamental design for a knife or other article of flatware, as shown.

FREDERICK E. GREENE.
